UNITED STATES PATENT OFFICE.

FRANK CANNON, OF POUGHKEEPSIE, NEW YORK.

DESIGN FOR A VEHICLE SIGNAL.

Application filed November 21, 1923. Serial No. 7,840. Term of patent 3½ years.

To all whom it may concern:

Be it known that I, FRANK CANNON, a citizen of the United States, residing at Poughkeepsie, in the county of Dutchess and State of New York, have invented a new, original, and ornamental Design for Vehicle Signals, of which the following is a specification, reference being had to the accompanying drawing, forming part thereof.

Figure 1 is a side elevation of a vehicle signal, showing my new design, and Figure 2 is an end view thereof.

I claim:—
The ornamental design for a vehicle signal as shown.

In testimony whereof, I affix my signature.

FRANK CANNON.
